UNITED STATES PATENT OFFICE

150,015

DESIGN FOR GIFT WRAPPING PAPER

Shirley Karlin, Bronx, N. Y.

Application May 20, 1947, Serial No. 139,148

Term of patent 3½ years

(Cl. D59—2)

To all whom it may concern:

Be it known that I, Shirley Karlin, a citizen of the United States, resident of the Borough of Bronx, county of Bronx, city and State of New York, have invented a new, original, and ornamental Design for Gift Wrapping Paper, of which the following is a specification, reference being had to the accompanying drawing, forming part thereof.

In the drawing, the figure shows a portion of gift wrapping paper showing my new design.

The design repeats horizontally on the drawing.

I claim:

The ornamental design for gift wrapping paper, substantially as shown and described.

SHIRLEY KARLIN,
